United States Patent Office

Des. 198,161
Patented May 12, 1964

198,161

BRASSIERE

William Charles Agatone, New York, N.Y., assignor to Maidenform, Inc., New York, N.Y.

Filed Nov. 13, 1963, Ser. No. 77,385

Term of patent 14 years

(Cl. D20—4)

Fig. 1

Fig. 2

FIG. 1 is a front perspective view of a brassiere showing my new design, the straps being shown broken away for convenience of illustration; and

FIG. 2 is a rear perspective view thereof.

I claim:

The ornamental design for a brassiere, as shown and described.
